(57) **CLAIM**

We claim, the ornamental design for a plunger for oral fluid collection device, as shown and described.

DESCRIPTION

FIG. 1 is a top right perspective view of a plunger for an oral fluid collection device in accordance with our new design.

FIG. 2 is a front view of the plunger of FIG. 1.

FIG. 3 is a back view of the plunger of FIG. 1.

FIG. 4 is a right view of the plunger of FIG. 1.

FIG. 5 is a left view of the plunger of FIG. 1.

FIG. 6 is a top view of the plunger of FIG. 1.

FIG. 7 is a bottom view of the plunger of FIG. 1.

FIG. 8 is a top front perspective view of the plunger of FIG. 1.

FIG. 9 is a bottom left perspective view of the plunger of FIG. 1.

FIG. 10 is a front view of the plunger of FIG. 1 in alignment with a funnel and collection tubes.

FIG. 11 is a top right perspective view of a second embodiment of the plunger of FIG. 1.

FIG. 12 is a front view of the plunger of FIG. 11.

FIG. 13 is a back view of the plunger of FIG. 11.

FIG. 14 is a right view of the plunger of FIG. 11.

FIG. 15 is a left view of the plunger of FIG. 11.

FIG. 16 is a top view of the plunger of FIG. 11.

FIG. 17 is a bottom view of the plunger of FIG. 11.

FIG. 18 is a top front perspective view of the plunger of FIG. 11.

FIG. 19 is a bottom left perspective view of the plunger of FIG. 11; and,

FIG. 20 is a front view of the plunger of FIG. 11 in alignment with a funnel and collection tubes.

The broken lines depict portions of the plunger form no part of the claimed design. The shade lines shown through the views are to indicate surface contour and are not intended to
